DRILL ASSEMBLY

John E. Gordon, Galt, Ontario, Canada, assignor to Joy Manufacturing Company, Pittsburgh, Pa., a corporation of Pennsylvania

Filed Nov. 27, 1962, Ser. No. 242,038

6 Claims. (Cl. 60—64)

This invention relates to a drill assembly and more particularly to a pressure fluid motor of the reciprocating piston type such as those used for powering an air leg drill to produce bores in mineral strata preparatory to blasting as a part of a mining operation.

The present invention provides a muffler, incorporated in the body of such a pressure fluid motor to reduce exhaust noise therefrom. Maximum attenuation of exhaust noise from an air driven pressure fluid motor is accomplished when pulsation in the exhaust air impinging upon the atmosphere is reduced to a minimum. Of the many ways of doing this by far the simplest is to provide an expansion chamber of sufficient volume that pulsations are absorbed within such chamber.

In the past such mufflers have been provided and have served the purpose but have not been satisfactory under all conditions of operation because they add substantially to the weight and size of the apparatus to which they are attached and as a further disadvantage have a tendency to freeze up due to condensation and freezing of the moisture within the exhaust air. A partial freeze up, while not interrupting the operation of the motor, does reduce the efficiency of such motor operation by increasing back pressure as is known.

The present invention contemplates provision of a muffler in the form of a thin metal shroud surrounding a major portion of the pressure fluid motor and radially spaced therefrom to provide sufficient enclosed volume for the desired reduction in exhaust air pulsation. By this means such volume is provided without materially increasing either the size or the weight of the pressure fluid motor and heat, developed in the motor during operation, conducted through the metal shroud prevents any substantial amount of freeze up during operation and causes rapid melting of any ice that may be formed whenever the operation is stopped during the normal drilling cycle.

It is therefore an object of this invention to provide a new and improved pressure fluid operated motor.

It is a further object of this invention to provide a new and improved pressure fluid operated motor having a muffler chamber for the attenuation of exhaust noise.

It is a specific object of this invention to provide a new and improved air operated pressure fluid motor provided with a thin metallic shell surrounding a major portion of the motor and radially spaced therefrom to provide sufficient enclosed volume for exhaust air expansion so that pulsations in the exhaust air are absorbed within the enclosed volume resulting in attenuation of exhaust noise.

These and other objects and advantages of this invention will be more readily apparent on consideration of the following description and drawings in which:

FIG. 1 is a top plan view of a pressure fluid motor constructed according to the principles of this invention;

FIG. 2 is a sectional view taken substantially on lines 2—2 of FIG. 1;

FIG. 3 is a sectional view taken substantially on lines 3—3 of FIG. 2;

FIG. 4 is an enlarged sectional view taken substantially on line 4—4 of FIG. 1;

FIG. 5 is an enlarged sectional view taken substantially on line 5—5 of FIG. 1.

In FIG. 1 there is shown a pressure fluid motor generally indicated at 10, of the type described and illustrated in U.S. Patent 2,922,396, comprising an elongated, hollow,

2

formed, generally cylindrical body member 11 having a forward end and a rearward end to the right and left, respectively, as viewed in FIGS. 1 and 2. A forward portion 12 of the body member 11 has a smaller diameter than the main portion of the body member 11 and forms therewith a forwardly sloping oblique shoulder 13 having, circumferentially spaced, raised ridge portions 14 upwardly extending from the oblique shoulder 13 and having upper surfaces generally parallel thereto. The body member 11 terminates rearwardly in an enlarged body portion 16 forming a peripheral shoulder 17 (see FIG. 3) about the main body portion of the body member 11.

Rigidly secured to the rearward end of the body member 11 is a hollow formed end member 18 which is rigidly secured to a rearwardly extending handle member 19 partially shown in FIGS. 1 and 2. The body member 11 has a stepped axial bore 21 therein having a cylinder portion 22 and a reduced diameter guide portion 23 slidably receiving different diameter portions of a stepped cylindrical piston member 24 reciprocable therein. An enlarged rearward portion 26 of the axial bore 21 suitably receives a suitable valve body 27 having a fluid actuated double valve 28 therein, and also suitably receives a rifle bar ratchet mechanism 29 designed to allow intermittent rotation of a helically splined rifle bar 31 in a single direction as is known. Intermediate the ends of the cylinder portion 22 is an enlarged bore portion 32 communicating with the exterior of the body portion 11 by way of exhaust ports or passageways 33 to provide for the exhaust of compressed air from the cylinder portion 22 during end portions of the forward and backward stroke of the piston 24 as is known.

A flexible fluid conducting line partially shown at 34 in FIG. 1 communicates, by way of a suitable bore 35 and a manually operable valve 36 through an annular passageway 37 in the end member 18, through suitable bores in the ratchet mechanism 29 and suitable passageways in the valve body 27, with the valve 28. The valve 28 being axially movable is biased by fluid pressure into forward or rearward positions to establish communication between the interior of the body 27 and suitable passageways in the body member 11 so that alternatively the forward and rearward faces of the piston member 34 are acted upon by pressure fluid in a manner well known in the art to cause reciprocation of the piston 24 within the cylinder portion 22.

A formed hollow, thin metallic casing or shell 40 radially outwardly spaced from the main body portion of the body member 11 is rigidly secured on the exterior peripheral surface of the enlarged body portion 16 in fluid tight relationship therewith and extends forwardly therefrom to the ridges 14 on the oblique shoulder 13. The shell 40 cooperates with the body member 11 to form a muffler chamber 41 of sufficient volume to absorb pulsations in the compressed air exhaust through the ports 33 as herein-after more fully described. The shell 40 has a semi-cylindrical upper portion 40' and inwardly sloping lower portions 42 (see FIG. 3) rigidly secured to the lower surface of the body member 11 as by welding. The forward edge of the shell 40 is supported by, and rigidly secured to, the upper rearward portion of the ridges 14 as by welding.

The forward edge of the shell 40 cooperates with the ridges 14 to form a plurality of passageways 46 from the chamber 41 to the ambient atmosphere. The passageways 46 are resiliently covered by a thin, arcuate, flexible diaphragm member 43 mounted on the outer surfaces of the ridges 14 and having an outer periphery mating with the outer surface of the semi-cylindrical portion 40' of the shell 40. The diaphragm member 43 has an inner periphery mating with the forward portion 12 to close the passageways 46. A portion of the outer surface of

the diaphragm member 43 inwardly adjacent its outer periphery and extending substantially the full length thereof is covered by an arcuate mounting plate 44 rigidly removably secured to the ridges 14 as by cap screws 45 threadedly engaged with suitable threaded bores in the ridges 14. The diaphragm member 43 is thus secured at circumferentially spaced points upon the outer surfaces of the ridges 14 with its outer periphery abutting the forward edge of the shell 40. The portion of the diaphragm 43 outwardly adjacent its inner periphery is free to be deformed outwardly and upwardly (see FIG. 5) by exhaust pressure as hereinafter more fully explained.

It is to be appreciated that the purposes of this invention can be accomplished by a casing such as the shell 40 formed as an integral part of the housing 11 so that the muffler chamber 41 becomes a part of the housing 11 similar to the water jacketing of an internal combustion engine.

In operating the fluid motor of this invention the fluid conducting line 34 is connected to a source (not shown) of pressure fluid hereinafter referred to as compressed air and through the communicating passageway 35 compressed air is supplied to the interior of the valve 36. Suitable operation of the valve 36 supplies compressed air through the annular passageway 37 and the passageways through the ratchet mechanism 29 to the interior of the valve body 27. At the beginning of such operation the piston 24 will be in a rearward position adjacent the valve body 27 and the valve 28 will be in a position to allow the passage of the compressed air from the interior of the valve body 27 into the cylinder portion 22 rearwardly of the piston 24 applying force to the rearward face thereof to move it forwardly as is known. As the piston moves forward it uncovers the enlarged bore portion 32 at the same time as the valve 28 is suitably activated to cut off the supply of compressed air from the rearward portion of the cylinder 22 while the compressed air within the rearward portion 22 is exhausted to the chamber 41 through the exhaust ports 33. Further action of the valve 28 connects the forward portion of the cylinder 22 with the source of compressed air and causes the piston 24 to be moved backwardly so that the enlarged bore portion 32 is first covered and then uncovered at the time when the valve 28 shuts off the flow of compressed air to the forward portion of the cylinder 22 and the compressed air in that portion of the cylinder is exhausted through the exhaust ports 33 into the chamber 41. Since the above described action takes place very rapidly, air is exhausted through the exhaust ports 33 in a series of sharp pulsations giving rise to the exhaust noise characteristic of such reciprocating type pressure fluid motors when being operated under normal conditions.

When air is exhausted from the exhaust ports 33 into the chamber 41 it displaces air already present in this chamber through the passageways 46 formed by the ridges 14 and raising the lower edge of the diaphragm 43 as shown in FIG. 5 such displaced air passes out into the atmosphere forwardly over the small diameter 12 of the body member 11 to mingle with the surrounding air. The volume of the chamber 41 is such that the pulsations of the air exiting through the exhaust ports 33 are almost completely absorbed therein so that the air exiting under the diaphragm 43 is relatively free of the sharp pulsations which give rise to exhaust noise. The flexible diaphragm 43 helps to damp the pulsations and is self adjustable to the volume of exhaust air associated with different speeds of operation of the pressure fluid motor 10 and further serves to prevent icing up of the exhaust orifice since any ice forming on the diaphragm 43 will be broken up by its flexing action into discrete particles which are swept out of the orifice formed by the diaphragm 43 and the reduced diameter portion 12 of the body member 11.

During continued operation of the fluid motor 10 cooling of the air due to its expansion from its formerly compressed state can cause condensation and freezing of

moisture from the air inside the chamber 41 on the interior of the shell 40. However, at the same time the body member 11 is being heated by the action of the compressed air within the cylinder 22 and as a result whenever the operation of the fluid motor is stopped the heat from the body member 11 conducted through the metal shell 40 melts such ice and thus prevents any undue accumulation of ice within the chamber 41.

It is to be appreciated that since operation of this device necessitates an operator grasping the handle 19 and positioned rearwardly of the motor 10, directing the exhaust forwardly over the reduced diameter of the motor 10 is advantageous in that dust is not blown into the operator's face and exhaust noise is further attenuated before reaching his ears.

Further advantages resident in the fluid motor of this invention are the provision of a sufficiently large chamber without significant increase in the size, weight or cost of the fluid motor 10 as compared to such motor without the noise reducing characteristics of the fluid motor of this invention.

A preferred embodiment of this invention having herein been described and illustrated it is to be realized that variations therein may be made without departing from the broad spirit and scope of this invention. Accordingly it is respectfully requested that this invention be interpreted as broadly as possible and be limited only by the prior art.

What I claim is:

1. A drill assembly comprising: a housing having a working chamber therein, a casing radially outwardly spaced from said working chamber to form a muffler chamber, at least one exhaust passageway communicating between said working chamber and said muffler chamber, said muffler chamber having an exterior opening, said housing having on the outer surface thereof at least a pair of axially and laterally outwardly extending portions abutting said casing to form an exhaust channel therebetween, said exhaust channel communicating between the exterior opening and ambient atmosphere, means normally closing said exhaust channel, said means being flexible to permit exhaust gases to flow outwardly through said channels.

2. A drill assembly comprising: an elongated housing having a working chamber therein, wall means radially outwardly spaced from said working chamber to form a muffler chamber, at least one exhaust passageway communicating between said working chamber and said muffler chamber, said muffler chamber having an exterior opening, said housing having on the outer surface thereof at least a pair of axially and laterally outwardly extending portions abutting said wall means to form an exhaust channel therebetween, said exhaust channel communicating between the exterior opening and ambient atmosphere, valve means normally closing said exhaust channel, and said valve means being flexible to permit exhaust gases to flow outwardly through said channel.

3. A drill assembly comprising: an elongated housing having a working chamber therein, a handle disposed adjacent one end of said housing, an elongated casing radially outwardly spaced from said working chamber to form a muffler chamber, one end of said casing being secured adjacent the handle end of said housing, at least one exhaust passageway communicating between said working chamber and said muffler chamber, said muffler chamber having an opening communicating with ambient atmosphere, said opening being disposed adjacent the other end of said casing, closure means normally closing said opening and being flexible to permit exhaust gases to flow outwardly through said opening.

4. A drill assembly comprising: a fluid operated motor having an elongated housing; a handle disposed adjacent one end of said housing; said housing having first wall means forming a cylindrical working chamber; second wall means radially outwardly spaced from said work-

ing chamber to form a muffler chamber; at least a portion of said first wall means between said chambers being formed of material which readily conducts heat; said second wall means having a first end and a second end; the first end of said second wall means being secured to the handle end of said housing in fluid tight relationship therewith; at least one exhaust passageway communicating between said working chamber and said muffler chamber; said muffler chamber having an exterior opening; a plurality of axially extended, circumferentially spaced, raised ridge portions of said housing supporting the second end of said second wall means; said raised ridge portions forming a plurality of exhaust channels communicating from the exterior opening to the ambient atmosphere; said exhaust channels being adjacent the second end of said second wall means axially spaced from the handle end of said housing so that exhaust fluid is directed away from the handle end of said housing; valve means normally closing said exhaust channels; and said valve means being flexible to permit exhaust gases to flow outwardly through said channels.

5. A drill assembly comprising: a fluid operated motor having an elongated housing; a handle disposed adjacent one end of said housing; said housing having first wall means forming a cylindrical working chamber; said working chamber having an output member reciprocatingly movable in a path therein; second wall means radially outwardly spaced from said working chamber to form a muffler chamber; at least a portion of said first wall means between the said chambers being formed of material which readily conducts heat; said second wall means having a first end and a second end; the first end of said second wall means being secured to the handle end of said housing in fluid tight relationship therewith; at least one exhaust passageway communicating between said working chamber and said muffler chamber; the motion of said output member controlling intermittent fluid flow through said exhaust passageway, and said muffler chamber having an exterior opening; a plurality of axially extended, circumferentially spaced, raised ridge portions of said housing supporting the second end of said second wall means; said raised ridge portions forming a plurality of exhaust channels communicating from the exterior opening to the ambient atmosphere; said exhaust channels being adjacent the second end of said second wall means axially spaced from the handle end of said housing so that exhaust fluid is directed away from the handle end of said housing; valve means normally closing said exhaust channels; and said valve means being flexible to permit exhaust gases to flow outwardly through said channels.

exhaust channels; and said valve means being flexible to permit exhaust gases to flow outwardly through said channels.

6. A drill assembly comprising: a fluid operated motor having an elongated housing; a handle disposed adjacent one end of said housing; said housing having first wall means forming an elongated cylindrical working chamber; said working chamber having an output member longitudinally reciprocatingly movable therein; second wall means radially outwardly spaced from said working chamber to form a muffler chamber; at least a portion of said first wall means between the said chambers being formed of material which readily conducts heat; said second wall means having a first end and a second end; the first end of said second wall means being secured to the handle end of said housing in fluid tight relationship therewith; a plurality of exhaust passageways communicating between said working chamber and said muffler chamber; the motion of said output member controlling intermittent fluid flow through said exhaust passageways; said muffler chamber having an exterior opening; a plurality of axially extended, circumferentially spaced, raised ridge portions of said housing supporting the second end of said second wall means; said raised ridge portions forming a plurality of exhaust channels communicating from the exterior opening to the ambient atmosphere; said exhaust channels being adjacent the second end of said second wall means axially spaced from the handle end of said housing so that exhaust fluid is directed away from the handle end of said housing; valve means normally closing said exhaust channels; and said valve means being flexible to permit exhaust gases to flow outwardly through said channels.
